UNITED STATES PATENT OFFICE.

ORA E. HOSKIN, OF PASADENA, CALIFORNIA.

BENCH-CLAMP.

1,259,742.

Specification of Letters Patent. Patented Mar. 19, 1918.

Application filed May 24, 1916. Serial No. 99,600.

To all whom it may concern:

Be it known that I, ORA E. HOSKIN, a citizen of the United States, residing at Pasadena, in the county of Los Angeles and 5 State of California, have invented certain new and useful Improvements in Bench-Clamps, of which the following is a specification.

This invention relates to work supporting clamps and more particularly to a 10 bench clamp.

The invention has more especial reference to a clamp which may be applied to the usual work bench without material alteration thereto, and has for its primary object, 15 the provision of a clamp, whereby various work may be supported thereupon and securely held in a desired position for the convenience of the user.

20 The invention also contemplates the provision of a device of the character stated, wherein a screw threaded shank member is provided and is adapted to, when rotated, move the clamp laterally so that the work 25 may be supported and secured thereby.

In the present construction, it is one of the aims and objects to simplify and reduce the cost of manufacture of constructions of this design and provide novel details in the 30 construction and arrangement of parts with a view to higher efficiency generally.

The improvements in the details and arrangement of parts may be apparent from an inspection of the accompanying drawings, in 35 connection with the specific construction hereinafter contained, and wherein the preferred embodiment of the invention is disclosed for the purpose of imparting a full understanding of the present improvements.

40 In the drawings:—

Figure 1 is a side elevation partly in section showing my improved device as applied to a portion of a work bench;

Fig. 2 is a front elevation of the clamp 45 supporting element; and

Fig. 3 is a fragmental detail in perspective of the work supporting and clamping member.

Referring now particularly to the drawings, wherein like reference numerals designate corresponding parts throughout the several views, the ordinary work bench as used in wood working is employed as a supporting means for my improved clamp. A

portion of one of the work benches, as used 55 in conjunction with the present device, is indicated by the numeral 1.

In order that the clamp may be attached to the bench, an opening 2 is arranged in one of the side portions thereof into which 60 openings is introduced a supporting element, designated in its entirety as at 3. This supporting element 3, to be inserted through the opening 2, must, of course, be inserted endwise thereinto and then, when 65 in the desired position, moved into the opening to a position as shown by the Fig. 1, and then the wedging block 2' is inserted in the opening 2. It is obvious that the clamping action of the device when the same is in use, 70 would tend to draw the supporting element to a vertical position, while when the structure is not in use, the positioning of the threaded shank as shown in Fig. 1, at which time the work supporting member is carried at quite a distance beyond the forward 75 surface of the supporting element would cause the weight of the outer end of the screw threaded shank together with the circular head thereof and the weight of the forward end of the work supporting member would constitute a fulcrum like action which would further hold the supporting element 80 in a vertical plane. It should also be noted that by positioning the wedging block 2' in 85 the opening, a flat inner and outer surface will be provided upon the work bench against which the material gripped by the vise may be brought to bear. It is also obvious the spurs upon the arms will assist in 90 holding the supporting element against shifting. The supporting element 3 comprises what may be termed a body portion or block 4, the said block being provided with a transversely disposed interiorly 95 threaded bore 5, for a purpose as will be subsequently apparent. A second opening 6 is arranged in the block and is so positioned as to be in proximity to the interiorly threaded bore, the same being substantially 100 rectangular in cross section. Engaging arms 7 and 8 are arranged upon the opposite sides of the body portion 4, the former being of greater thickness and having arranged thereupon, spurs 9, whereby the same may 105 be positively engaged with the adjacent portion of the work bench, thus, preventing further movement thereof. The engaging arm

8 is formed upon the lower outer face of the body 4 and is so arranged as to be offset therefrom, thereby permitting the same to be engaged with the opposite face of the adjacent portion of the work bench. Spurs 10 are also arranged upon the contacting face of the arm 8, for a purpose as heretofore described. It will be obvious, that when the supporting element has been inserted through the opening 2, lateral movement thereof will be prevented by the peculiar formation of the body portion 4, which is snugly received by the opening 2 and further, by reason of the spurs 9 and 10 as arranged upon the receiving arms 7 and 8. Due to the arrangement of the engaging arms 7 and 8, longitudinal movement of the block will also be prevented.

A work receiving and supporting member, having an elongated flattened leg portion 11 and a head portion 12 is receivable by the opening 6, in such a manner as to permit sliding movement thereof. The head portion 12 has arranged thereupon a guide member or housing 13, the under surface of which is concaved as at 14, this side member consisting of a laterally extended arm. The lower extremity of the head portion 12 is concaved as shown at 15, the purpose of which shall be now described.

A screw threaded shank 16 is engageable with the interiorly threaded bore 5 and has arranged upon one end thereof, a circular head 17, which head carries an operating seat 18, whereby the shank 16 may be turned into engagement with the said interiorly threaded bore. In normal position, the circular head 17 is engaged with the head portion 12, while the adjacent portion 40 of the screw threaded shank 16 is received by the concaved portion 15, formed in the lower extremity of the head portion. The guide member is consequently, also engaged with the circular head 17 and more specifically, engages the periphery thereof, by reason of the concaved lower face 14. In reviewing the operation of the device and assuming that the various constituent elements have been assembled, a board or other object is placed upon the support 11. The operating seat 18 is then turned, which motion, causes the screw threaded shank 16 to be engaged with the complementary screw threaded bore 5, as arranged in the body portion 4 and thereby, causes the said shank to be advanced therewith. Upon continued rotation of the shank portion 16, the circular head 17, due to its engagement with the head portion 12, will carry the supporting member inwardly, the opposite extremity of said supporting member being supported by the opening or way 6, as arranged in the body portion 4. The guide member 13 provides means whereby the adjacent extremity of the supporting member may be

supported, the same being transmitted to the circular head portion 17 of the screw threaded shank 16. To release the work as clamped by the device, it is only necessary that the shank portion 16 be turned in an opposite direction, thus, retracting the same and causing the supporting element to be withdrawn through the opening or way 6, this being accomplished by means of the elongated lower extremity of the head portion 12, which snugly engages that portion of the screw threaded shank 16, as adjacent the circular head 17 thereof.

Should it be desired, the operating member 18 may be replaced by a crank member, whereby rotation of the screw threaded shank 16 may be expedited.

While I have herein disclosed a specific embodiment of the invention, it will be apparent to persons skilled in the art, that the invention is capable of embodiment in other forms and devices differing in detail and arrangement from that shown, as may be in keeping with the hereto appended claims.

Having thus described the invention, what is claimed is:

1. In a device of the class described, the combination of a supporting element comprising a body having at each end an arm, said arms extending in opposite directions, thus allowing the body to be positioned upon a support, at which time said arms will engage the opposite surfaces of the support for retaining the body in a correct position, said body having a threaded bore extending therethrough, said body also having a flat opening formed therethrough parallel to said threaded bore, a screw threaded shank passing through said threaded bore, means for rotating said screw threaded shank, a work supporting element mounted upon said screw threaded shank and projecting through said opening, whereby as said shank is moved said work supporting member will be moved on said body.

2. In a device of the class described, the combination of a supporting element constituting a body having at each end an arm, said arms extending in opposite directions, said body being adapted to be positioned upon a support at which time said arms will engage the opposite side of the support for holding said body in a correct position, said body having a threaded bore projecting therethrough, said body also having a rectangular opening extending therethrough, a screw threaded shank projecting through said screw threaded bore, said shank having a circular head upon its outer end, a work supporting member comprising an elongated flat portion provided with a vertical head at its outer end, said head having a guide portion extending at right angles thereto, said guide portions having a concaved under surface, the lower end of said head being

concave and bearing upon said screw threaded shank, said circular head bearing upon the concaved portion of said guide, whereby as said screw threaded shank is rotated, said circular head will bear upon the head of said work supporting member for urging the same inwardly, at which time said elongated flat portion will pass through said rectangular opening, thus causing said

work supporting member to be moved with 10 respect to said body.

In testimony whereof I affix my signature in presence of two witnesses.

ORA E. HOSKIN.
